US00D720214S

(12) United States Design Patent
De Pietri Tonelli et al.

(10) Patent No.: US D720,214 S
(45) Date of Patent:  Dec. 30, 2014

(54) PACKAGING CONTAINER BLANK

(71) Applicant: Tetra Laval Holdings & Finance S.A.,
Pully (CH)

(72) Inventors: Roberto De Pietri Tonelli, Colombaro
di Formigine (MO) (IT); Marcello
Barbieri, Modena (IT); Marco
Marchetti, Carpi (MO) (IT); Davide
Morciano, Modena (IT); Stefano Costa,
Casalmaggiore (CR) (IT); Per
Lagerroth, Eslöv (SE)

(73) Assignee: Tetra Laval Holdings & Finance S.A.,
Pully (CH)

() Term: 14 Years

(21) Appl. No.: 29/476,386

(22) Filed: Dec. 12, 2013

(30) Foreign Application Priority Data

Jul. 26, 2013 (EM) 002282137

(51) LOC (10) Cl. 09-03

(52) U.S. Cl.

USPC D9/433
